INSTRUMENT FOR DEFINING ARCS AND IRREGULAR CURVES

Oscar H. Nelson, Peshtigo, Wis.

Application December 14, 1938, Serial No. 245,722

2 Claims. (Cl. 33—176)

My invention relates to improvements in instruments for defining arcs and irregular curves and has as one of the principal objects thereof the provision of an instrument of the above described character which is simple in construction, durable in use, efficient in operation and economical in manufacture.

Another object of my invention is to provide a device of the character described which may be readily adjustable to conform to the contour of a surface and utilized in a manner whereby the contour may be delineated on another surface.

Other objects and advantages will be apparent from the following description, appended claims and annexed drawing.

Referring to the drawing wherein like reference characters designate like parts throughout the several views:

Figure 1 is a side elevation of my invention, the parts thereof being arranged to define the contour of a concave surface.

Figure 2 is a transverse sectional view taken on the line 2—2 of Figure 1.

Figure 3 is a horizontal detail sectional view taken on the line 3—3 of Figure 1.

Figure 4 is a detail sectional view taken on the line 4—4 of Figure 1.

Figure 5 is a detail side elevation of one of the end hooks partly in section.

Figure 6 is a bottom plan view of the end hook.

Figure 7 is a detail side elevation of one of the ends of the bars, partly in section, and depicting the means for maintaining the arms of said bar in spaced relation.

My novel form of instrument comprises a pair of bars 5, the inner ends of which are pivotally connected by means of a hinge 6. Each of said bars is provided with a pair of spaced arms 7, the outer ends of which are connected together in spaced relation by means of a spacer 8 secured therebetween by a bolt 8a. The inner ends of said arms are connected to one of a pair of hinge leaves 9 of the hinge 6.

The hinge leaves 9 are fashioned with serrated abutting faces 10 and with registering openings 11 through which extends an eye bolt 12. The eyed end of the bolt 12 has slidably mounted therein an adjusting rod 13 and the opposite end of said bolt has threaded thereon a lock nut 14 whereby to clamp the hinge leaves together and secure the rod 13 in adjusted position against one of the outer faces of said leaves as clearly illustrated in Figure 2 of the drawing.

Slidably mounted on the bars 5 is a plurality of spaced blocks 15 fashioned with recesses 16

accommodating therethrough the spaced arms 7 of the respective bars. Slidably mounted in the blocks 15, between the arms 7, are eye bolts 17, the eyed ends of which have slidably mounted therein adjusting rods 18 of a like construction 5 as the rod 13. The opposite ends of the bolts 17 have threaded thereon lock nuts 19 bearing against the outer faces of the blocks 15 and serving to clamp the rods 18 against the opposite faces of the respective arms 7 whereby to maintain said 10 rod in adjusted position relative to the bars. The lower ends of the rods 13 and 17 are provided with spherical heads 20 whereby to preclude withdrawal of said rods from the respective eye bolts.

The opposite ends of the rods 13 and 17 are 15 threadedly fixed within housings 21 and which are provided with tongues 22 pivotally connected between the bifurcated ends of blocks 23 by means of bolts 24. A block 23 is provided for each of the rods 13 and 17 as clearly illustrated 20 in Figure 1 of the drawing and secured to said blocks is a resilient pliable strip 25 by means of screws 26.

The faces of the strip 25 are provided with scale markings denoting inches and fractions 25 thereof. The ends of the strip 25 have secured thereto semi-circular guides 27 on which are mounted arcuate shaped members 28 fashioned with slots receiving therethrough screws threaded into the guides 27. The members 28 are adapted 30 to be adjusted over the ends of the strip 25 for engagement with the ends of adjacent surfaces when desired. When not in use, the members 28 are adjusted in the opposite direction to effect clearance with the ends of the strip. 35

In use, the rods 13 and 17 are adjusted relative to the respective eye bolts to enable the strip to conform to the contour of a desired surface. When thus adjusted, the lock nuts are tightened to secure said rods in fixed position relative to 40 the bars thereby permitting the contour defined by the strip 25 to be delineated on another surface.

My instrument is especially adaptable in instances where it is desirous of forming a number 45 of like templets and also for use in connection with the hulls of ships and the like in developing the irregular curves thereof.

It is also obvious that the invention is not confined to the herein described use therefor as it 50 may be utilized for any purpose to which it is adaptable. It is therefore to be distinctly understood that the invention is not limited to the specific construction as illustrated and described, as the same is only illustrative of the principles of 55

operation which are capable of extended application in advance forms, and that the invention comprehends all construction within the scope of the appended claims.

5. What is claimed is:

1. A device of the character described, comprising, hinged pairs of spaced bars, blocks slidably mounted between the bars of each pair and provided with sections overlying one face of the 10 bars, an eye bolt slidably extending through each block, rods slidably extending through the eyes of said bolts and slidably engaging the opposite face of said bars, a flexible strip pivoted to the ends of said rods and adjustable therewith with 15 respect to said blocks to define a desired contour, and means operable on said bolts and engaging said sections to clamp said rods and said blocks to said bars against relative movement to maintain said strip in a condition defining said contour.

2. A device of the character described, comprising, connected pairs of spaced bars, blocks mounted on the bars of each pair and fashioned with spaced channels slidably accommodating said spaced bars, a member slidably extending 5 through each block, rods extending through said members and slidably engaging the bars on the opposite sides thereof with respect to the blocks, a flexible strip pivoted to the ends of the rods and adjustable with the latter with respect to the bars 10 to define a desired contour, and means mounted on said members and engaging said blocks and operable against said blocks for clamping said rods and said blocks to said bars against relative movement to maintain said strip in a desired configuration with respect to said bars. 15

OSCAR H. NELSON.
